United States Patent Office

Des. 210,175
Patented Feb. 13, 1968

210,175

REFLECTING TRAFFIC GUIDE OR SIMILAR ARTICLE

John B. Keats, Marietta, Ohio, and Roger G. Royer,
Parkersburg, W. Va., assignors to Borg-Warner Corpora-
tion, Chicago, Ill., a corporation of Illinois

Filed Nov. 4, 1966, Ser. No. 4,547

Term of patent 14 years

(Cl. D72—1)

FIG. 1

FIG. 2

FIGURE 1 is a side elevational view of a reflecting traffic guide or similar article showing my new design, the opposite side being a mirror image of the side shown; and

FIGURE 2 is an end elevational view thereof, the opposite end being a mirror image of the end shown.

We claim:

The ornamental design for a reflecting traffic guide or similar article, substantially as shown and described.
